UNITED STATES PATENT OFFICE.

HANS HAUGNES, OF GARRISON, NORTH DAKOTA.

SPRING DRILL-EYE.

1,054,841.

Specification of Letters Patent. Patented Mar. 4, 1913.

Application filed June 5, 1911. Serial No. 631,427.

To all whom it may concern:

Be it known that I, HANS HAUGNES, a citizen of the United States, residing at Garrison, in the county of McLean and State of North Dakota, have invented a new and useful Spring Drill-Eye, of which the following is a specification.

This invention relates to improvements in what may be termed drill or tool cable attaching devices.

The invention has for its object to provide for relieving the device, including its actuating cable, of a sudden jerking action, which would otherwise occur under unusual circumstances or conditions.

A further object is to allow the tool or drill to have a resilient action in performing the boring or drilling operation, especially in actuating the drill or tool from, or with a steel cable.

A still further object is to provide for securing an effective and substantial connection between the tool or drill and its actuating cable and to insure the tool or drill receiving a turning action for suitably effecting the boring or drilling operation.

A still further object is to carry out the aforesaid ends in a simple, expeditious and effective manner.

The invention consists of certain instrumentalities and features substantially as hereinafter fully disclosed and defined in the claims.

In the accompanying drawing illustrating the preferred embodiment of my invention, wherein it will be understood that various changes may be made as relates to the details of the construction and arrangement of the parts without departing from the spirit of the invention: Figure 1 is an elevational view of the device. Fig. 2 is a like elevation viewing the device in a direction at right angles to the point of view of Fig. 1. Fig. 3 is a sectional elevation of the device. Figs. 4 and 5 are transverse sections thereof as produced upon the lines 4-4 and 5-5, of Figs. 1 and 2, respectively, viewing in the direction of the arrows.

Referring to the figures by characters of reference 1 designates a tool engaging member having one end portion broadened, as at 6, and provided with slightly concaved sides converging toward the free end of the member 1 so as thus to constitute a wedge. Fitted upon the opposed concave faces of the wedge 6 are the thickened lower ends

13 of guide strips 2, these strips being substantially uniform in width, as will be apparent by referring to Fig. 2, and each having a flat inner face and a rounded outer face. Those ends of the guide strips 2 remote from the thickened ends 13 are formed with enlargements 10 constituting abutments for a tie ring 9 which, as shown, is provided with diametrically opposed spacing lugs 11 extending between the enlargements 10. Another tie ring 8 is mounted on the guide strips 2 close to the thickened portions 13 and mounted on the guide members 2 is a coiled spring 7 the ends of which bear against the rings 8 and 9 respectively.

A flat bar 3 is slidably mounted between the guide members 2 and between the lugs 11, this bar being provided at one end with an eye 4 or the like while its other end is provided with oppositely extending ears 12 projecting beyond the thickened portions 13 and under the tie ring 8.

In assembling the parts of the device, the guide strips 2 are placed opposite to each other with their flat faces in contact whereupon the thickened portions 13 thereof can be inserted successively through the ring 9, spring 7 and ring 8. This is obviously permissible in view of the fact that the combined thickness of the portions 13 is less than the internal diameters of the rings 9 and 8 and of the spring 7. The lugs 11 are inserted between the enlargements 10 so as to hold the strips 2 properly spaced after which bar 3 is inserted longitudinally successively into ring 8, spring 7, and ring 9 so as to bring the wings or ears 12 against the ring 8. The last step followed in assembling the parts is the insertion of the wedge 6 between the thickened portions 13, this wedge being secured to said thickened portions by transverse bolts 5. Thus it will be seen that all of the parts are fixedly connected and cannot become accidentally displaced as the result of any jolting to which the device may be subjected. Spring 7 acts as a cushion, permitting relative movement of the guide strips 2 and the bar 3, it being obvious that when the strips 2 move downwardly relative to the bar 3, the ring 9 and enlargements 10 will move with the strips 2 and thus compress spring 7 against the ring 8. The wedge 6 of course holds the lower portions of the side strips 2 properly spaced so that they will not bind to an objectionable extent upon the bar 3. The upper ends

of the side strips are held against objectionable binding by the lugs 11.

What is claimed is:—

1. A device of the class described including spaced tie rings, a coiled spring interposed therebetween and bearing thereagainst, spacing lugs upon one of the rings, opposed guide strips insertible through the rings and spring and having enlargements at one end adapted to contact with one of the rings, said spacing lugs projecting between the enlargements, a flat bar slidable between the guide strips and between the lugs, there being oppositely extending ears upon the bar and bearing upwardly against one of the tie rings, a tool engaging member, and a wedge-like member carried thereby and extending between and secured to the guide strips, said guide strips having thickened portions which, when spaced apart by the wedging members, coöperate with the enlargements on the guide strips to hold the tie rings against withdrawal from the guide strips.
2. A device of the class described including spaced tie rings, spacing lugs upon one

of the rings, a coiled spring interposed between and bearing against the rings, guide strips each having an enlargement at one end and a thickened portion at its other end, 30 said strips being movable in contact and insertible, while in contact, through the rings and spring, a bar slidable between the strips, means on the bar for engaging one of the rings, the lugs on the other ring, constituting means for holding the guide strips spaced at one end to prevent the withdrawal of said end from the tie rings, a tool engaging member, and a spacing member carried thereby and insertible between the thickened 40 portions of the guide strips to hold said portions spaced apart to prevent their withdrawal from the rings, said wedging member and thickened portions being secured together.

In testimony that I claim the foregoing as my own, I have hereto affixed my signature in the presence of two witnesses.

HANS HAUGNES.
